US00D972604S

(12) **United States Design Patent** (10) **Patent No.:** **US D972,604 S**
(45) **Date of Patent:** **** Dec. 13, 2022**

(54) **PORTABLE TIRE INFLATOR**

(71) Applicant: **Fuzhou Huodan Electronic Technology Co., Ltd.**, Fuzhou (CN)

(72) Inventor: **Yixuan Xu**, Shenzhen (CN)

(**) Term: **15 Years**

(21) Appl. No.: **29/820,223**

(22) Filed: **Dec. 21, 2021**

(51) **LOC (13) Cl.** **15-02**

(52) **U.S. Cl.**

USPC **D15/9**; D15/7

(57) **CLAIM**

The ornamental design for a portable tire inflator, as shown and described.

DESCRIPTION

FIG. 1 is a front and top perspective view of a portable tire inflator, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the portable tire inflator that form no part of the claimed design.

1 Claim, 8 Drawing Sheets
